WINDOW REGULATOR

Austin Gudmundsen, Milwaukee, Wis., assignor to
 Briggs & Stratton Corporation, Milwaukee, Wis.,
 a corporation of Delaware

Application January 25, 1933, Serial No. 653,359

3 Claims. (Cl. 16—200)

This invention relates to certain new and useful improvements in window regulators and refers more particularly to window regulators appropriate for automotive vehicles and the like.

5 In the conventional window regulator now in use, the side channel guides are the only means provided to prevent rattling of the glass when in its lowered or intermediate positions. This fact has necessitated a close fit between the 10 guideways and the glass pane, and inasmuch as the dimensions of the glass and also of the window openings cannot be held to the required close limits, it has been customary to place shims in back for the channel guideways. This work 15 requires skilled labor and obviously adds considerably to the cost of production.

Also, inasmuch as the modern trend in automobile body design demands windows of irregular shape, that is, with the sides at angles to 20 each other, the difficulty of preventing rattling of the window pane has been further increased.

Another disadvantage of the conventional window regulator is that the necessity for a specific location of the crank handle precludes the 25 mounting of the regulator at its most advantageous position with reference to the weight of the glass and the range of adjustment, or requires a complicated regulator design. These disadvantages have proved objectionable to manufacturers of automobiles, and it is an object of this invention to provide a regulator of such simplified design and construction as to entirely overcome these and other objections to existing regulators.

30 One of the primary objects of this invention is to provide a regulator wherein the usual hand crank is entirely eliminated.

Another object of this invention is to provide a regulator so designed and constructed that the 35 window pane may be readily adjusted to any desired position and secured there against displacement by vibration and also firmly held against rattling.

Another object of this invention resides in the 40 provision of common means for clamping the window pane in any position of adjustment to prevent rattling and for locking the window pane in any position.

Another object of this invention resides in the 45 provision of simple means for positively locking the window closed to preclude unauthorized opening from the outside.

More specifically, it is an object of this invention to provide a window regulator in which the 50 weight of the glass is so balanced by one or more

springs that the raising and lowering of the window pane may be effected by the application of force directly to the glass.

And a further object of the invention resides in the provision of novel means for connecting 5 the regulator arms and the window pane.

With the above and other objects in view which will appear as the description proceeds, my invention resides in the novel construction, combination and arrangement of parts substantially 10 as hereinafter described and more particularly defined by the appended claims, it being understood that such changes in the precise embodiment of the herein disclosed invention may be made as come within the scope of the claims. 15

In the accompanying drawings, I have illustrated several complete examples of the physical embodiment of my invention constructed according to the best modes I have so far devised for the practical application of the principles there- 20 of, and in which:

Figure 1 is a plan view of part of an automobile door having portions broken away and illustrating the application of the regulator of this 25 invention thereto;

Figure 2 is a detail view partly in section and partly in top plan taken on the plane of the line 2—2 of Fig. 1;

Figure 3 is a cross section view taken through Fig. 1, on the plane of the line 3—3;

Figure 4 is a cross section view taken through Fig. 1, on the plane of the line 4—4;

Figure 5 is a detail section view through the lower edge portion of the window pane taken on the plane of the line 5—5 of Fig. 1;

Figure 6 is a detail view in side elevation of the structure shown in Fig. 5;

Figure 7 is a view similar to Fig. 1, illustrating a modified embodiment of this invention;

Figure 8 is a cross section view taken through 40 Fig. 7 on the plane of the line 8—8;

Figure 9 is a cross section view similar to Fig. 3, but illustrating another manner of locking the window pane closed;

Figure 10 is a cross section view similar to Fig. 45 9, and illustrating the parts in their inoperative position;

Figure 11 is a view looking up on the plane of line 11—11 in Fig. 9.

Referring now more particularly to the accompanying drawings in which like numerals indicate like parts throughout the several views, the numeral 10 represents the glass window pane of an automobile door, mounted in any desired manner for vertical movement to and from a 50

closed position. Inasmuch as the application of this invention is not limited to any particular type of window pane installation, the window opening and the usual channel guides in which the glass pane slides have not been shown. As is customary, the glass pane 10 is mounted for vertical movement between the inner and outer walls 11 and 12 respectively, of the automobile door or body.

10 The window sill is formed by directing the upper portions of the inner and outer walls 11 and 12 inwardly, as at 13 and 14, respectively. As best illustrated in Fig. 3, the inwardly directed portions or flanges 13 and 14 terminate short of each other to afford the necessary space through which the glass pane moves. The sill portion formed by the flange 13 of the wall 11, is reinforced by a wood cross bar 15 held in position by a downward extension 16 of the flange portion 13 and tongues 17 at its lower marginal edge directed outwardly to underlie the wood cross piece.

15 The regulator, which has been generally designated 18, is mounted from a cross panel 19 which may be part of the inner wall 11, and in the case of an automobile door, extends from one side of the door to the other. The regulator 18 counterbalances the weight of the window glass and enables the glass to be raised and lowered without effort, as will be hereinafter more fully described.

20 The regulator per se is of simple construction and comprises a base plate 20 attached to the panel 19 by screws threaded into studs 21. The particular design and construction of the base plate is immaterial, but it is preferably formed of sheet metal stamped to form and provided with flanges at its peripheral edges to increase its rigidity.

25 Pivots mounted on the base plate are two arms 22 and 23. The pivotal mounting of the arm 22 consists merely of a stud 24 either anchored solidly in the arm and journaled in the base plate or anchored in the base plate and journaled in the arm, and the pivotal mounting for the arm 23 comprises a stud 25 having one end fixed to the arm and its opposite end enlarged and projected beyond the base plate in which it is journaled to afford a mounting for a counter-balance spring 26.

30 The manner of attaching the spring 26 is conventional. One end thereof is engaged in a slot 27 formed in the stud 25 and its other end is hooked about a pin 28 fixed to the base plate. The direction of the convolutions of the spring is such that it yieldably urges the arm 23 to a raised position.

35 To coordinate the motion of the arms 22 and 23, gear segments 29 and 30 are rigidly attached to their inner ends with their pitch radii concentric to the pivotal mountings 24 and 25 so as to be in mesh at all times. In this manner, the single spring 26 acts on both arms, but if desired it is readily apparent that a second spring may be provided to operate on the arm 22.

40 The outer free ends of the arms 22 and 23 are connected to the window pane, as at 31. The specific construction of the connection 31 is of novel design to insure maximum freedom of action. The connection embodies flanges 32 projected downwardly from the channel 10 in which the lower edge of the window pane is rigidly secured in the customary manner. These flanges 32 have elongated slots 33 enlarged at their inner ends as at 34 to afford entrances for attaching

buttons 35 carried at the outer ends of the arms.

45 Obviously, when the window pane is to be assembled with the regulator, the arms occupy positions at which their buttons 35 will be aligned with the enlarged ends 34 of the slots, and similarly when it is necessary to remove the glass, it must be raised to an abnormal position to permit the required alignment of the buttons 35 with the enlargements 34. The marginal edges of the slots 33 are formed as smooth guideways 10 or tracks 36 by curling inwardly the marginal edge portions of the slots.

50 The specific construction of the buttons 35 at the outer ends of the arms is best shown in Figs. 5 and 6. These buttons are really slide blocks 15 and consist of cylindrical blocks 37 of fiber or other suitable material, having their lower portions cut away at an inclination to the axis of the blocks to afford a flat inclined surface 38. The diametrically opposite upper portions of the blocks have a V-shaped slot 39 cut therein, the apex of which lies parallel to the plane surface 38.

55 Each block of fiber 37 is mounted on a stud 40 rigidly fixed to the outer end of one arm, as at 41, the block having a relatively loose fit 25 on the stud and being held on the stud by an enlarged head 42.

60 When engaged in their respective slots in the manner hereinbefore described, the blocks are held against any possible play to insure a smooth 30 sliding connection. The means for completely taking up all play consist of an expansive spring 43 coiled about the stud and confined between the adjacent end portion of the regulator arm and a cupped washer 44 positioned on the stud 35 with its marginal edge bearing against the flange 32. The action of the spring 43 tends to pull the block or button through the slot and by reason of the inclination of the flat surface 38, this action of the spring at all times holds the block 40 securely against one side of the guides 36 so that all possible play is taken up. The loose fit of the block 37 on the stud permits the same to adjust itself to any irregularities.

65 Actuation of the window pane is effected by 45 the direct application of a lifting or lowering force to the window pane. For convenience in manipulating the window pane, a handle 45 is attached to its upper edge. The specific construction of this handle may be varied to suit 50 different requirements, but it is desirable to provide a structure which will be readily accessible when the window is in its fully lowered position and also when the window is in its uppermost position. The handle as illustrated in Fig. 1, 55 meets these requirements and comprises a clamp member 46 adapted to be clamped to the upper edge of the window pane and a bail 47 hinged to the clamp. The bail 47 is so constructed that when the window pane is moved 60 to its lowermost position, it is automatically lifted by the window sill to project upwardly where it may be easily grasped and in all other positions it hangs downwardly to afford ready means of applying force to the window pane.

70 Accidental actuation of the window pane by vibration is prevented by a novel locking device now about to be described.

75 At a central point, the sill portion, comprising the wood cross bar 15 and its metal sheath, 70 mounts a handle 48. The inner end of this handle is secured to the upper end of a rod 49 journaled in a vertical bore formed in the wood cross piece 15 and extending through the top flange 13 and the adjacent tongue 17. A cross 75

pin 50 driven into a hole in the upper end of the rod 49 and having its ends received in slots formed in an upstanding flange 51 on the handle serves to lock the handle to the rod. The lower 5 end of the rod 49 is journalled in a bearing 52 carried by the base plate 20 of the regulator and is directed laterally to provide a right angular extension 53 for a purpose to be later described. Longitudinal shifting of the rod is pre- 10 cluded by the handle 48 at its top and abutments 54 on the rod in engagement with the under surface of the tongue 17.

The inner end of the handle 48 is covered by the usual finish molding 55 which encircles the 15 window opening, and the outer end of the handle projects through a slot 56 in the molding to permit the handle to be swung about the axis of the rod 49.

An upstanding cylindrical flange 57 is formed 20 on the inner end of the handle eccentric to the axis of the rod 49, and encircling this flange is a fiber ring 58. The peripheral edge of the ring 58 bears against the inner face of the glass upon proper actuation of the handle 48 as best illustrated in Fig. 2. In Fig. 2, the handle is shown 25 in its position holding the fiber ring against the glass.

At a point directly opposite the engagement of the ring 58 with the glass is a rubber bumper 30 button 59. This rubber bumper is conveniently mounted in an aperture 60 formed in the down-turned flange 61 on the outer wall 14. With the handle 48 moved to its unlocking position shown in dotted lines in Fig. 2, the ring 58 is 35 moved sufficiently far from the rubber bumper 59 to afford clearance for the glass. This unlocked condition is best illustrated in Fig. 10.

When it is desired to secure the window pane 40 in an adjusted position, the handle 48 is swung to the left with reference to Fig. 2, to its full line position shown therein. In this position, the fiber ring bears directly against the glass pane slightly compressing the rubber bumper button 59 and holding the glass pane against rattling.

45 Simultaneously with the actuation of the handle carried cam to clamp the glass pane, locking means carried by the regulator mechanism is placed in its operative condition by the lower laterally directed end 53 of the rod 49. This 50 locking means comprises a shiftable dog 63 mounted on a shelf 64 struck from the base plate 20. While the manner of mounting the dog is immaterial, it is obtained in the present instance by two rivets 65 secured to the shelf and 55 slidable in elongated slots 66 formed in the dog.

An upright flange 67 formed on the dog and preferably overlying the adjacent face of the base plate, has a hole 68 for the reception of the right angularly directed lower end 53 of the 60 rod 49, so that radial swinging movement thereof, effected by turning of the rod, imparts movement to the locking dog. It is noted that the base plate 20 is cut away in back of the upright flange 67 to accommodate the outermost 65 end of the lateral extension 53.

The forward operative end of the locking dog 63 is engageable in the spaces between the teeth of a gear wheel 69 rotatably mounted on the base plate and rigidly connected with a pinion 70 meshing with the segment 29 of the regulator arm 22.

70 Through the pinion 70, a desirable gear reduction is afforded between the gear wheel 69 and the movement of the regulator arms, so that 75 a comparatively large movement at the periphery

of the gear wheel represents but a small motion on the part of the regulator arms. This permits a fine adjustment of the position of the window pane.

Obviously, when the locking dog 63 is engaged with the gear wheel 69, actuation of the regulator arms and consequently the glass pane is precluded and the structure is so designed that when the handle 48 is swung to its position holding the fiber ring against the glass pane, 10 the locking dog 63 will be in its operative position.

To prevent the possibility of leaving the window pane in an unlocked position, a spring 71 is provided to yieldably urge the locking dog at all times to its operative position. This spring 15 may be of any design, but in the present instance is shown as a torsion spring coiled about one of the studs mounting the base plate, and having one end engaging with the locking dog and its other end anchored to the base plate. 20

It will be noted that when the handle 48 is in its normal position at which the window pane is secured against actuation, it is slightly past dead center with respect to the eccentric clamping cam, so that a positive effort is required to 25 move the same to its unlocking position. Rotation of the rod 49 and consequently swinging movement of the handle 48 is limited in this slightly past dead center position by the engagement of the locking dog with the gear wheel 69. 30

From the description thus far, it is seen that a single easily manipulated handle effects a positive locking of the window pane and also clamps the glass and securely holds it against rattling.

If it is desired, the locking means afforded by 35 the engagement of the dog 63 with the gear wheel 69 may be omitted. The clamping action afforded by the ring 58 and the rubber bumper 59 is then depended upon to secure the window pane against accidental actuation. However, a positive lock against opening of the glass when in its fully closed position is afforded by directing a right angular extension 73 from the rod 49 at a point at which it will just pass underneath the channel 10' at the lower edge of the glass, as ill- 45 lustrated in Fig. 9.

In this construction, the right angular extension 73, besides affording a positive lock to secure the window in its fully closed position, serves to hold the rod 49 and the handle in a position at 50 which the handle is slightly beyond dead center and clamping the window glass, as hereinbefore described. To this end, the extension 73 is formed of such length that its outer extremity abuts against the face of the glass pane when 55 the handle is in its desired position just slightly beyond dead center.

The specific structure for locking the regulator arms against movement is also susceptible to modification, and in Figs. 7 and 8, another embodiment of this feature is shown. In this embodiment no means are shown to clamp the glass pane, but it will be readily apparent that a clamping device such as that described, may be added. However, with the structure shown in Figs. 7 and 65 8, actuation of the clamping device would be independent of the actuation of the holding mechanism which will now be described.

The holding mechanism consists of an elongated arm 74 pivotally mounted as at 75 from 70 the base plate 20 and extending upwardly to a point adjacent the cross piece 15. Here the arm 74 is directed laterally to afford a handle 76 which extends through a slot 77 formed in the molding 75. Also pivoted on the stud 75 is a second arm 75

78, the outer free end of which is provided with a locking dog 79 engageable in the spaces between the teeth on a gear wheel 80 rotatably mounted from the base plate on a stud 81. A 5 pinion 82, rigid with the wheel 80, meshes with one of the gear segments to be driven thereby.

The short arm 78 carrying the locking dog 79 is yieldably urged to a position engaging the dog with the gear wheel 80 by a spring 83. This 10 spring is conveniently coiled about the pivot stud 75 and has its outer ends engaged with the arms 74 and 78 as illustrated. With the arm 74 in its position illustrated in Fig. 7, the spring 83 is free to engage the dog with the gear wheel, but when 15 the arm 74 is moved to its dotted line position illustrated in Fig. 7, an upstanding flange 84 on its inner end, by engaging the arm 78, holds the same from contact with the gear wheel as shown in dotted lines. A retaining bridge 85 provides 20 convenient means for holding the arm 74 in either of its positions of adjustment.

From the foregoing description, taken in connection with the accompanying drawings, it will be readily apparent to those skilled in the art, 25 that this invention affords an exceptionally simple and practical window regulator which because it entirely eliminates the usual hand crank, permits mounting of the regulator at the most advantageous location with respect to the weight 30 distribution of the window. This location is usually central between the sides of the window pane and thus permits the use of arms of maximum length which in turn permits a more equal distribution of the force of the counterbalancing 35 spring.

In this connection, it is desired to point out that while the spring has been defined as being of such strength as to just balance the weight of the window throughout substantially its entire 40 movement, it may be so formed as to impart a slight elevation to the window pane whenever it is released from its extreme lowermost position. With the spring so designed, the handle 45 need not project above the edge of the glass when in its lowermost position.

What I claim as my invention is:

1. In combination with a movable window pane, a member connected with the window pane and provided with an elongated slot substantially 50 parallel to the adjacent edge of the window pane, a swinging arm, and means carried by the swinging arm and engageable in the elongated slot to effect a connection between the arm and window pane, said means comprising a shaft rigidly

mounted on the arm and provided with a fixed abutment at a distance from the arm, a block loosely mounted on said shaft, said block having a groove cut in one side for engagement with one edge of the elongated slot and having a flat surface inclined with respect to the axis of the shaft for engagement with the other edge of the slot, the inclination of the flat surface being such that the block is wedged securely between the edges of the slot upon the application of a pull 10 on the shaft away from its said fixed abutment, and spring means interposed between the arm and the member having the slot to apply the yielding force onto the shaft in said direction. 5

2. In combination with a window pane movable past a window sill, counterbalancing mechanism beneath the window sill and connected with the window pane to counterbalance the window pane to an extent enabling free actuation of the window pane to any position by the application of a slight force directly on the window pane, holding means operable on said counterbalancing mechanism for holding it and consequently the window pane against actuation in either direction at any one of many definitely spaced predetermined positions of adjustment, including a toothed member movable with the counterbalancing mechanism, a dog slidable to and from engagement with the teeth of said toothed member, a vertical rod journaled in the 30 window sill and connected with the dog to shift the same toward and from engagement with the toothed member upon rotation of said rod, and a manually operable handle attached to the rod above the window sill to turn the same. 35

3. In combination with a wall having a window opening provided with a sill and a glass pane movable to and from a position closing the window opening, an upright shaft rotatable in the window sill, means for positively holding the 40 glass pane in any adjusted position including a rotatable tooth member, means connecting the toothed member with the window pane so that the toothed member turns upon ascent and descent of the window pane, a holding dog movable to and from engagement with the toothed periphery of said toothed member, a connection between the upright shaft and the dog whereby rotation of the shaft shifts the dog into and out of operative engagement with the toothed member, and a handle connected with the shaft above the window sill to turn the shaft. 45 50

AUSTIN GUDMUNDSEN.
